UNITED STATES PATENT OFFICE.

JOHN J. MORSE, OF ST. LOUIS, MISSOURI.

REINFORCED BRAKE-SHOE.

1,075,848.

Specification of Letters Patent.

Patented Oct. 14, 1913.

Application filed August 19, 1912. Serial No. 715,706.

To all whom it may concern:

Be it known that I, JOHN J. MORSE, a citizen of the United States, residing in the city of St. Louis and State of Missouri, have invented certain new and useful Improvements in Reinforced Brake-Shoes, of which the following is a specification.

This invention relates to certain new and useful improvements in brake-shoes, and has for its object to provide an improved brake-shoe having novel and efficient means for reinforcing the back of same, so that the structure is strengthened at points subjected to the greatest strain and, also, so that in case the brake-shoe becomes broken in use the parts of same will be held together by the reinforcing means.

In the accompanying drawings forming part of this specification, in which like numbers of reference denote like parts wherever they occur, Figure 1 is a top plan view of a brake-shoe embodying the present invention; Fig. 2 is a sectional view on the line 2—2, Fig. 1; Fig. 3 is a sectional view on the line 3—3, Fig. 1; and, Fig. 4 is a skeleton perspective view of the reinforcement.

Referring to the drawings, the brake-shoe is designated 1, and is preferably formed of cast-iron, though, if desired, may be formed of relatively hard and soft metals as is frequently the case in order to obtain increased frictional and wearing qualities, said brake-shoe having the usual end stop lugs 2 formed on the back thereof to brace the ends of the brake-head (not shown in the drawings) and bearing the usual key lug 3 which has an opening 4 for the reception of the brake-shoe key or pin (not shown), which opening 4 is preferably arranged to extend longitudinally of said brake-shoe.

The back of the brake-shoe 1 is reinforced by means of a pair of rods 5 formed of wrought, ductile, or other tough metal, though, of course, bars, wires, or the like may be used in place of the rods 5. These rods 5 are located at or adjacent to the back of the brake-shoe and are preferably arranged to extend longitudinally of the brake-shoe. At the middle of the brake-shoe the rods 5 are spaced apart and are arranged to extend substantially parallel to each other underneath the side-walls 6, respectively, of the lugs 3. The rods 5 converge from the lug 3 so as to meet at the points 7 intermediate the lug 3 and each lug 2, at which points 7 said rods are bent

or twisted around each other or otherwise connected as best seen in Figs. 1 and 2. From the points 7 where the rods 5 are bent or twisted around each other, the end portions of the rods 5 diverge from the points 7 and then extend substantially parallel to each other toward the ends of the brake-shoe where the extreme ends of said rods are preferably bent upwardly so as to project into the lugs 2, thereby anchoring the ends of the rods 5 firmly in the ends of said brake-shoe. The rods 5 greatly strengthen the brake-shoe and by reason of same being bent or twisted around each other intermediate the lug 3 and each lug 2, the brake-shoe is greatly strengthened at its weakest parts, namely the parts intermediate the lugs 3 and each lug 2. The lug 3 is also reinforced by means of a rod 8 formed of wrought, ductile, or other tough metal, or a plurality of such rods, a pair of same being depicted in the drawings for the purpose of illustration. Each rod 8 is bent into a U-shaped configuration, so as to straddle the opening 4 in said lug 3 and to have the ends project into the body of the brake-shoe, which ends are bent so as to form stirrups 9, through which the middle parts of the rods 5 pass, as best seen in Figs. 3 and 4, thereby anchoring the ends of said rod 8 firmly in the body of the brake-shoe 1.

It should be understood that bars, wires, or the like, formed of wrought, ductile, or other tough metal may be substituted for the rods 8, if so desired.

It should be noted in the drawings that, for the purpose of illustration, the rods 5 have been bent or twisted around each other at the points 7 intermediate the lug 3 and each lug 2 in such a manner that the middle part of each rod 5 is located near one side of the back of the brake-shoe while the ends of same are located near the opposite side of the back of the brake-shoe, but it should be understood that said rods 5 may be bent or twisted in any other manner at the points 7 intermediate the lug 3 and each lug 2 so that the middle point of each rod 5 and the ends thereof will be located near the same side of the back of the brake-shoe.

Heretofore, brake-shoes have been reinforced by means of rods which were bent or twisted together only at a point underneath the key lug and spaced apart from the key lug to the ends of the brake-shoe, and the key lug was reinforced by means of

a ring-shaped rod or a plurality of ring-shaped rods through which the twisted parts of the rods in the back of the brake-shoe extended, but, when so reinforced, the 5 twisted parts of the rods in the back of the brake-shoe together with the ring-shaped rod or rods in the key lug made such a bulk of the wrought metal underneath the key lug that the cast metal was chilled too 10 quickly and caused to "blow" at this particular point, when the cast metal was poured around same. This defeated the purpose of the reinforcement in the middle part of the back of the brake-shoe. This 15 objectionable feature is obviated by the present invention in which the rods 5 are spaced apart at the middle of the brake-shoe so as not to form a bulk of wrought metal with the rods 8, thus preventing the cast 20 metal from becoming chilled too quickly or from "blowing" when poured around the rods 5 and 8. The fact that the rods 5 are twisted together intermediate the key lug 3 and each end lug 2 renders the brake-shoe 25 stronger at these points than when the rods extend straight between the key lug 3 and the end lugs 2.

I claim:

1. A brake-shoe having a pair of rods located adjacent to the back thereof, said rods being spaced apart at the middle and ends of the brake-shoe and twisted together intermediate the middle and ends of same. 30

2. A brake-shoe having a lug at each end thereof and a pair of rods located adjacent to the back of same, said rods being spaced apart at the middle and ends of the brake-shoe and twisted together intermediate the middle of the brake-shoe and each end lug. 35

3. A brake-shoe having a lug at each end thereof and a pair of rods located adjacent to the back of same, said rods being spaced apart at the middle and ends of the brake-shoe and twisted together intermediate the middle of the brake-shoe and each lug, the 40 ends of said rods being anchored in said end lugs.

4. A brake-shoe having a middle lug with an opening extending therethrough, a pair 45 of rods located adjacent to the back of the brake-shoe, said rods being spaced apart at the middle and ends of the brake-shoe and being bent inwardly intermediate said middle lug and each end of the brake-shoe so that the bent parts of said rods contact with each other, and a U-shaped rod located in said middle lug and straddling the opening therein.

5. A brake-shoe having a middle lug with 50 an opening extending therethrough, a pair of rods located adjacent to the back of the brake-shoe, said rods being spaced apart at the middle and ends of the brake-shoe and secured together intermediate said middle lug and each end of the brake-shoe, and a 55

U-shaped rod located in said middle lug and straddling the opening therein, the ends of said U-shaped rod being embedded in the body of the brake-shoe and bearing stirrups to receive said first-mentioned rods. 70

6. A brake-shoe having a middle lug with an opening therethrough, a pair of rods located adjacent to the back of the brake-shoe, said rods being spaced apart at the middle and ends of the brake-shoe and twisted together intermediate said middle lug and each end of the brake-shoe, and a plurality of U-shaped rods located in said middle lug and straddling the opening therein, the ends of each of said U-shaped rods being embedded in the body of the brake-shoe and bearing stirrups to receive said first-mentioned rods. 75

7. A brake-shoe having a lug at each end thereof and a middle lug with an opening 80 extending therethrough, a pair of rods located adjacent to the back of the brake-shoe and having their ends anchored in said end lugs, said rods being spaced apart at the middle and ends of the brake-shoe and twisted together intermediate said middle lug and each end lug, and a U-shaped rod located in said middle lug and straddling the opening therein, the ends of said U-shaped rod being anchored to said first-mentioned rods. 85

8. A brake-shoe having a lug at each end thereof and a middle lug with an opening extending therethrough, a pair of rods located adjacent to the back of the brake-shoe 90 and having their ends anchored in said end lugs, said rods being spaced apart at the middle and ends of the brake-shoe and twisted together intermediate said middle lug and each end lug, and a plurality of U-shaped rods located in said middle lug and straddling the opening therein, the ends of each of said U-shaped rods being anchored to said first-mentioned rods. 95

9. A brake-shoe having a pair of rods located adjacent to the back thereof, said rods being spaced apart at the middle and ends of the brake-shoe and connected intermediate the middle and each end of same. 100

10. A brake-shoe having a lug with an opening therein located intermediate the ends of the brake-shoe, a pair of rods located adjacent to the back of the brake-shoe, said rods being spaced apart underneath said lug and at the ends of the brake-shoe and being connected intermediate said lug and each end of the brake-shoe, and a U-shaped rod located in said lug and straddling the opening therein, the ends of said U-shaped rod being anchored to said first-mentioned 115 rods. 120

11. A brake-shoe having a lug with an opening therein located intermediate the ends of the brake-shoe, a pair of rods located adjacent to the back of the brake-shoe, 125

5 said rods being spaced apart underneath said lug and at the ends of the brake-shoe and being connected intermediate said lug and each end of the brake-shoe, and a plurality of U-shaped rods located in said lug and straddling the opening therein, the ends of each of said U-shaped rods being anchored to said first-mentioned rods.

10 12. A brake-shoe having a lug with an opening therein located intermediate the ends of the brake-shoe, a pair of rods located adjacent to the back of the brake-shoe, said rods being spaced apart underneath said lug and at the ends of the brake-shoe 15 and being connected intermediate said lug and each end of the brake-shoe, and a plurality of U-shaped rods located in said lug and straddling the opening therein, the ends of each of said U-shaped rods being anchored to said first-mentioned rods, the ends

of said first-mentioned rods being anchored in the ends of the brake-shoe.

13. A brake-shoe having a reinforcement embedded therein consisting of a pair of rods which have spaced end portions and a plurality of portions intermediate said end portions which are bent inwardly and are interlocked with each other. 25

14. A brake-shoe having a reinforcement embedded therein consisting of a pair of rods, said rods having inwardly extending bowed portions which are interlocked with each other. 30

35 In testimony whereof I hereunto affix my signature in the presence of two witnesses.
